R. O. MOORE

ROTARY DRILL BIT

Filed Nov. 6. 1924

Fig. 1.

Fig. 2.

Fig. 3.

WITNESS

WITNESS

A technical line drawing of a mechanical assembly. At the top, a rectangular block labeled '10' has a circular hole labeled '9'. A vertical slot labeled '11' is positioned below the hole. A cylindrical component labeled '12' is shown in an exploded view, revealing a central eyelet. A second rectangular block labeled '10' is shown below the first, with a slot labeled '11' and a circular hole labeled '9'. A cylindrical component labeled '13' is shown below the second block. A small cylindrical component labeled '17' is shown to the left of the second block. The drawing is labeled 'K.O.4.' at the top center.

INVENTOR

RALPH O. MOORE,
BY *Mauri Koo*
ATTORNEYS

UNITED STATES PATENT OFFICE.

RALPH OTIS MOORE, OF WEWOKA, OKLAHOMA.

ROTARY DRILL BIT.

Application filed November 6, 1924. Serial No. 748,202.

To all whom it may concern:

Be it known that I, RALPH O. MOORE, a citizen of the United States, and resident of Wewoka, in the county of Seminole and

5 State of Oklahoma, have invented certain new and useful Improvements in Rotary Drill Bits, of which the following is a specification.

My invention relates to improvements in 10 rotary drill bits for use in drilling wells or like operations, more particularly to improvements in rotary drill bits of the so-called fish-tail type of construction, and it consists in the combinations, constructions 15 and arrangements herein described and claimed.

As is well known, a drill bit of the above mentioned type of construction ordinarily is formed with the head thereof provided 20 with a pair of integral depending cutter extensions which soon become dull in use, necessitating the removal of the entire bit for resharpening of the cutter portions thereof. Ordinarily, it is necessary that the bit be 25 heated in a suitable furnace, and then provided with a sharp edge and tempered after the bit has become dull. It will be appreciated that a considerable delay in the drilling operation may result from the necessity 30 of removing the only available bits for resharpening and repair or else a considerable supply of sharp bits must be kept on hand at all times, which would cause considerable expense.

35 An object of the present invention is to provide a drill bit of the character described which has simple, inexpensive and readily removable cutter members supported on the head of the drill bit and adapted to be replaced quickly and without the use of any special tools when required.

40 A further object of the invention is the provision of a drill bit of the character described which has means for cutting in advance of the bit head at the center of the drill bore as well as at the outer edge of the drill bore.

45 A further object of the invention is the provision of a drill bit having a central cutter element mounted to rotate about an axis

which extends at right angles to the longitudinal axis of the drill bit and being adjustable about its axis of rotation to vary the portion of the cutting edge thereof that will be presented to the work.

55 Other objects and advantages will be apparent from the following description, considered in conjunction with the accompanying drawings, in which,

Figure 1 is a side elevation of a drill bit 60 embodying the invention applied to the lower end of a drill stem,

Figure 2 is an elevation of the structure 65 shown in Figure 1, the view being at right angles to Figure 1,

Figure 3 is a bottom plan view of the improved drill bit, and

Figure 4 is a perspective group view 70 showing the cutter members of the drill bit and a shaft for supporting one of said cutters.

A drill bit embodying the invention has a head 1 formed with a reduced tapering axial attaching portion or shank 2 at the normally upper end thereof. The attaching portion or shank 2 is shown as being provided with external screw threads for engaging with an internally screw threaded tapering axial socket 3 in the lower end of a drill stem 4, a shoulder 5 being defined 75 at the juncture of the shank 2 and the head 1 for engagement with the lower end of the drill stem 4 when the shank 2 has been screwed tight in the socket 3. Any thrust 80 from the drill stem 4 thus will be imparted to the head 1 through the shoulder 5 without any undue strain of the threaded connection between the shank 2 and the drill stem 4.

The head 1 is provided at its lower end 85 with a pair of depending integral extensions 6. The lower end portions of the respective extensions 6 are shown as extending laterally of the bit head. The inner side faces of the respective extensions 6 are 90 shown as lying in a vertical plane which extends centrally of the bit head while the outer faces of the extensions preferably are convexly curved or rounded off at their lower ends and at their outer lateral edges as 100

- clearly shown in the drawings. The inner faces of the extensions 6 are provided with transverse rabbets 7 which extend from the lower ends of the extensions for possibly 5 half the length thereof. The upper wall of each of the rabbets 7 is inclined upwardly and inwardly from its outer edge as best seen in Figure 2 at 8. Each of the rabbets 7 constitutes a seat or socket for a removable cutter blade or plate 9 which has the upper end wall thereof beveled as indicated at 10 to conform to the inclination from the horizontal of the upper wall 8 of its seat. Each of the cutter plates 9 also has the lower end wall thereof beveled as indicated at 11 and has the outer face thereof concavely curved as indicated at 12 so that the outer edge of the lower end wall of the cutter plate is a sharp cutting edge.
- 10 Each cutter blade 9 is secured in place in its seat by means of a bolt 13 and nut 14 or like fastening means so that the beveled upper end wall of the cutter plate will fit closely against the inclined upper wall of 15 the seat and the lower end portion of the cutter plate will depend slightly below the level of the extension 6 on which the cutter plate is supported. The cutter plate thus will be held rigid with the extension 6 on 20 which it is supported but can be removed quickly and easily for the purpose of replacement or repair. The thickness of the cutter plate preferably is such that the outer face thereof will be substantially flush with 25 the inner face of the extension 6 on which it is supported. Each cutter plate also has the outer lateral wall thereof beveled as indicated at 15 to provide a lateral cutting edge.
- 30 35 40 45 50 55 60 65 70 75 80 85 90 95 100 105 110 115 120 125 130
- With the arrangement of depending extensions spaced apart as described in the foregoing, a vertical space or aperture will be defined at the lower end of the bit head as indicated at 16 between the inner lateral walls of the extensions 6. A horizontal shaft 17 extends transversely across the space 16 and has the end portions thereof supported in aligned seats indicated generally at 18, each of which may be formed partly in an inner face of one of the extensions 6 and partly in the adjacent face of the cutter plate 9 which is secured to that particular extension 6, the portion of the seat 18 that is formed in the extension 6 of course being in the vertical wall of the rabbet 7 of said extension so that the shaft 17 will be held against displacement from position to extend across the space 16 so long as the cutter plates 9 are held against displacement from the rabbets 7. Removal of the cutter plates 9 will permit displacement of the shaft 17. A circular cutter 19 having the cutting edge thereof located intermediate its ends is supported on the shaft 17 to rotate about the axis of the latter and is held against axial

movement on the shaft 17 by the engagement of the ends of the cutter 19 with the inner lateral wall of the extension 6.

From the foregoing description of the various parts of the device, the operation thereof may be readily understood. The cutter plates 9 and the circular cutter 19 are made of suitable material, such as a high grade tool steel. These cutters are comparatively small and therefore can be replaced when required at slight expense. Moreover, the replacement of the cutters 9 and 19 or any one of these cutters can be effected quickly and easily without the use of any special tools. The cutting edge portion of the drill cutter 19 depends below the lower cutting edges of the plates 9 and thus serves to start the drilling of a bore at the center of the latter before the lateral cutters 9 cut into the earth. The cutter 19 can be turned from a given position to present a different portion of the annular cutting edge thereof to the work when the portion of the cutting edge that has been in use has become dull.

Obviously, my invention is susceptible of embodiment in forms other than that illustrated in the accompanying drawings and I therefore consider as my own all such modifications and adaptations of the form of the device herein described as fairly fall within the scope of the appended claims.

I claim:

1. A rotary drill bit comprising a head formed with a pair of spaced apart depending extensions at the lower end thereof, said extensions being located eccentrically of the bit head and having the inner faces thereof disposed in a vertical plane which extends centrally of the bit head, each of said extensions having a seat in its inner face at the lower end thereof for a cutter plate, means for releasably securing said cutter plates to said extensions in engagement with their seats, and a circular cutter supported between said extensions for rotation about an axis which extends at right angles to the longitudinal axis of the bit head.
2. A rotary drill bit comprising a head formed with a pair of spaced apart depending extensions at the lower end thereof, said extensions being located eccentrically of the bit head and having the inner faces thereof disposed in a vertical plane which extends centrally of the bit head, each of said extensions having a seat in its inner face at the lower end thereof for a cutter plate, means for releasably securing said cutter plates to said extensions in engagement with their seats, a shaft extending between said extensions at right angles to the longitudinal axis of the bit head and having the end portions thereof supported between said cutter plates and said extensions, and a circular cutter mounted on said shaft between said extensions and being rotatable about the axis

of said shaft, said circular cutter depending below the level of the lower edge of said cutter plates.

3. A rotary drill bit comprising a head formed with a pair of spaced depending extensions at the lower end thereof, a shaft of greater length than the distance between said extensions, cutter plates secured to said ex-

tensions and serving to clamp the opposite edge portions of said shaft to said extensions 10 so that the shaft extends across the space between the extensions and a circular cutter supported on said shaft for rotation between said extensions.

RALPH OTIS MOORE.
